UNITED STATES PATENT OFFICE.

STANTON C. MARTIN, OF ERIE, PENNSYLVANIA, ASSIGNOR, BY MESNE ASSIGNMENTS, TO ERIE CITY IRON WORKS, A CORPORATION OF PENNSYLVANIA.

PULVERIZER BEATER.

Application filed June 1, 1922. Serial No. 565,060.

To all whom it may concern:

Be it known that I, STANTON C. MARTIN, a citizen of the United States, residing at Erie, in the county of Erie and State of Pennsylvania, have invented new and useful Improvements in Pulverizer Beaters, of which the following is a specification.

This invention is designed to improve the construction of the beaters for pulverizers particularly pulverizers used in pulverizing coal for immediate consumption in furnaces. With such pulverizers the coal is pulverized and the fuel carried through the pulverizer with the air for combustion.

These pulverizers rotate at a very high speed so that great strength is required. At the same time it is desirable to have the construction as light as possible. Further it is also desirable to have the beater blades carried by the device removable so that they may be renewed as they wear. With the present invention the carrier for the blades is built up of steel as distinguished from a cast structure and the blades are lightened and simplified in structure.

The invention is illustrated in the accompanying drawings as follows:

Fig. 1 shows a central vertical section through the beater.

Fig. 2 an end view, partly in section.

Fig. 3 a plan view of a beater blade and securing bar.

Fig. 4 a side elevation of a beater blade.

Fig. 5 an enlarged section of a beater blade and a portion of the support.

Fig. 6 a plan view of blades having tapered bases.

Fig. 7 a side elevation of the same.

Fig. 8 an end view of the blades.

1 marks the shaft on which the beater is mounted and two end pieces which are connected by a pipe 3 to form the hub of the beater carrier. The pieces 2 have the flanges 4 on which are secured the discs 5. The discs 5 have the flanges 6 on their outer peripheries and a conical shell 7 is secured to these flanges.

Supporting T bars 8 are secured to the flanges 6 by means of rivets 9. These T bars form undercut grooves 10. Beater blades 11 have the bases 12 with the extensions 13 engaging the undercut portions of the grooves. The blades, therefore, are positively secured holding them against the strains to which they are subjected by rea-

son of the impact of the material and the centrifugal force due to rotation. The blades are held in the grooves by plates 14 at the ends of the grooves.

Due to the very high rotation the bars are not ordinarily strong enough to sustain the force where they are secured only at their ends. I have improved this by supplying rings 15 which have the tapered flanges and to which the bars are secured by rivets 16. As many of these rings may be supplied as is necessary to sustain the force. They are formed in an ordinary flanging machine and being of wrought metal, or steel have a great tensile strength.

In order to readily fit the blades which are in the form of castings I prefer to have the bottom surfaces of the bases tapered from a line 17 intermediate the edges. This reduces the amount of grinding necessary to fit the blades for the grooves and inasmuch as when they are in action the entire force is outwardly against the undercut portions the line 17 forms an ample base.

In order to reduce the weight I provide the depressions 18 at the rear of the blades. The bars may be tapered or the blades tapered.

In Fig. 5 the base is of slightly different conformation from that shown in the other figures, the tapered underface being omitted.

What I claim as new is:

1. In a pulverizer beater, the combination of a carrier having undercut grooves in its periphery; and beater blades having bases arranged in said grooves with portions extending under the undercut portions of said grooves and the under sides of the bases being bevelled from a longitudinal line intermediate their edges.

2. In a pulverizer beater, the combination of a rotary carrier having undercut grooves in its periphery; and beater blades arranged in said grooves, said beater blades having depressions in their rear faces reducing the centrifugal strain incident to the rotation of the blades.

3. In a pulverizer beater, the combination of a hub comprising supporting flanged discs on the hub; T bars secured to the flanged discs, said T bars having their central extensions radially disposed and their cross extensions at their outer edges forming undercut grooves in the periphery of the

carrier; sectional beater blades arranged in the grooves; and means for locking said blades in the grooves.

4. In a pulverizer beater, the combination
5 of a hub comprising supporting flanged discs on the hub; T bars secured to the flanged discs, said T bars forming undercut

grooves in the periphery of the carrier; sectional beater blades arranged in the grooves; and a supporting flanged ring intermediate 10 the discs to which the T bars are secured.

In testimony whereof I have hereunto set my hand.

STANTON C. MARTIN.
